COMBINED NIGHT LIGHT AND MEMO PAD AND PENCIL HOLDER ATTACHMENT FOR A TELE-PHONE

Meyer Ostrie, New York, N.Y.

Application December 3, 1958, Serial No. 53,639

Term of patent 3½ years

(Cl. D26—14)

FIG. 1

FIG. 3

Fig. 1 is a side elevational view of a combined night light and memo pad and pencil holder attachment for a telephone, showing my new design;

Fig. 2 is a top plan view; and

Fig. 3 is a fragmentary perspective view thereof.

The broken line showing of a representative telephone, a memo pad and a pencil are for illustrative purposes only.

I claim:

The ornamental design for a combined night light and memo pad and pencil holder attachment for a telephone, substantially as shown and described.
